MODULATING SYSTEM AND METHOD

Application filed April 4, 1928. Serial No. 267,257.

This invention relates generally to systems and method of effecting modulation of a carrier wave. It is particularly designed for use in radio receiving systems.

5 An object of the invention is to vary the resistance of a circuit element uniformly at a periodic rate without resorting to the use of a device having moving contacts or any other mechanically moving parts.

10 Another object of the invention is to modulate a received continuous wave at an audible rate in a simple and effective way whereby the signal may be made perceptible.

15 My system and method may be outlined briefly as utilizing an electron relay having the usual input and output circuits, which are arranged to pass radio or carrier frequency energy. Connected across points of different potential of these circuits there is a gas discharge tube having cold electrodes. This gas 20 discharge tube is excited in such a manner that its resistance is repeatedly broken down, with a result that the resistance across the two points of different potential is repeatedly 25 varied between finite and infinite values. In the preferred form of my invention the system is incorporated in a radio receiver in which the electron relay has its input circuit associated with a suitable source of signal 30 energy of carrier frequency.

Referring to the drawing:

Figure 1 is a circuit diagram illustrating one form of my system and method.

Fig. 2 is another circuit diagram illustrating another form of my system and method.

To describe my invention more specifically, in Fig. 1 I have shown a suitable form of electron relay 11 capable of repeating signal energy of carrier or radio frequencies. The conventional relay shown by way of example utilizes a cathode 12 of the filamentary type, anode or plate 13 and grid or control element 14. Some form of radio frequency circuit 40 is associated with the input of relay 11, as for example an inductance 16 tuned as by means of variable capacitance 17. Since in the preferred embodiment of my invention I utilize relay 11 for integrating signals, I have 45 shown a grid condenser 18. A suitable grid

leak resistance 19 is also shown connected between the grid and cathode.

In order to provide regeneration of energy 5 repeated by the relay 11, I preferably provide a suitable feed back circuit such as is provided by an inductance 21 included in the plate circuit 13, and which is inductively coupled to inductance 16. For controlling the degree of regeneration I have shown a variable capacitance 22 connected in series with inductance 21 and the cathode 12. When the energy in the output of relay 11 is integrated it may be translated directly or may be further amplified before being impressed upon a translator. Where relay 11 serves solely as an amplifier 60 and not as an integrating device, radio frequency current from its output circuit is impressed upon a further integrating device before being translated. As explained above, since in my preferred system I utilize grid 65 condenser 18 and grid leak 19, the relay 11 serves both as an integrating and an amplifying device. To secure further amplification of the integrated signals however I prefer to couple a suitable audio frequency 70 amplifier 23 to the output of relay 11 and to supply a suitable translator 24 from the output of this amplifier. As a suitable means for coupling together relay 11 and amplifier 75 23, I have shown an audio frequency transformer 25 having its primary winding connected in series with "B" battery 26 and the output circuit of relay 11. A suitable radio frequency choke 27 is preferably inserted between transformer 24 and the inductance 21. 80

As a suitable source of signal energy of carrier frequency, I may either directly couple the input of relay 11 to a carrier wave transmission line or to a radio antenna, or the coupling may be effected thru one or more 85 stages of radio frequency amplifiers. In the drawing for simplicity I have shown a radio antenna 28 connected to the high potential side of the input of relay 11, thru the series tuning condenser 29.

90 For effecting modulation of signal energy repeated thru relay 11, I preferably utilize a gas discharge tube 31 having the usual cold cathode and anode electrodes 32 and 33. Gas discharge tubes are well known in the art 95 100

and consist of anode and cathode electrodes operated at normal temperatures and enclosed within an evacuated vessel. The vessel contains one or more readily ionizable gases such as neon, argon, helium, zenon, hydrogen and the like, at relatively low pressure. Tubes of this type have practically infinite resistance or impedance until the potential across their electrodes is increased 10 above a certain critical value, after which the resistance is broken down and a current flow occurs. After a current flow has been initiated the resistance of the tube is relatively low.

15 There are a number of ways in which a gas discharge tube may be excited so that its resistance is repeatedly broken down at a rate which is at least a musical frequency. For example it may be excited by a pulsating or 20 alternating current to repeatedly break down the resistance of the tube at a frequency equal to the current impulses, or it may be excited from a direct current source in series with a high resistance. For simplicity I have shown the latter arrangement 25 which consists of a suitable source of direct current such as a battery 34 connected across the electrodes of tube 31 in series with a high resistance 36. The potential applied by 30 battery 34 is preferably substantially greater than the potential necessary to break down the resistance of tube 31. With such an exciting circuit the resistance of the gas discharge tube is broken down at a substantially 35 constant frequency, the frequency being determined by the characteristics of the exciting circuit and by the characteristics of the gas discharge tube 31. In general it may be stated that the frequency may be 40 controlled by varying resistance 36, by placing a variable capacitance across the electrodes of tube 31, or by placing such a capacitance in shunt with resistance 36. I have 45 shown an adjustable capacitance shunted across resistance 36, as for example by providing a fixed condenser 37 shunted by a variable condenser 38. With this arrangement of a fixed and variable condenser, closer control may be had than by using a 50 single variable condenser.

For cooperatively associating the gas discharge tube with the remainder of the system, I preferably connect the same across two points of different potential of the radio 55 frequency circuits of relay 11. For example two such points of different potential are formed by the terminals of variable condenser 22, which in that form of the invention shown in Fig. 1 has been shown as connected to the gas discharge tube 31 thru leads 39 and 41. In order to prevent audio frequency impulses set up in the exciting circuit from tube 31 from being fed back into the circuit of relay 11, I preferably utilize blocking condensers 42 and 43 inserted

in series with lead 41, this lead being connected to the high potential side of condenser 22. This arrangement is made more effective by the use of a radio frequency choke 44 which will pass audio frequency impulses 70 set up by tube 31, but which will act as a choke for radio frequency currents. As the cathode of relay 11 and therefore likewise lead 39 is preferably grounded as by means of ground connection 45, I also preferably 75 utilize a radio frequency choke 46 in series with the anode of tube 31 in order to prevent radio frequency currents from passing to ground through battery 34.

With the system as explained above, it 80 will be apparent that when the tube 31 is in operating condition, that is when its resistance is being broken down at periodic intervals by its exciting circuit, the circuit which includes this tube and which is connected across the points of different potential located at opposite sides of variable condenser 22, will have its values of resistance periodically varied. In other words the arrangement is substantially equivalent to periodically bypassing the radio frequency currents in condenser 22 thru a resistance. As a result the signal currents being repeated by relay 11 are modulated by frequency corresponding to the frequency of operation of 90 gas discharge tube 31. Such modulation results chiefly from the repeated variation of the resistance component of the radio frequency circuits, although to a certain degree it is caused by the detuning effect of 95 the low impedance path provided thru the gas discharge tube. For reception of continuous wave telegraphic signals, I prefer to operate the gas discharge tube at an audible or tone frequency so that energy of this 100 tone frequency is repeated thru amplifier 23 and impressed upon the translator 24. Because of the manner in which the audio frequency impulses set up in the exciting circuit of tube 31 are prevented from passing 110 into the circuits of relay 11, no currents of tone frequency are received by the translator during intervals when no signal energy is being received.

I have found that with this receiving system, the relay 11 can be operated in far more sensitive condition than without the use of such a modulating device. In other words with my modulating device in operation, the amount of regeneration may be greatly increased without causing the relay to spill over into local oscillation. While this mode of operation is believed novel as applied to my system, it is to be understood that the system is practically operative for the reception of signals without utilizing regenerative action to a greater degree than would be present if my modulation device were not employed.

In Fig. 2 I have shown a modification of 130

my system and method, in which the gas discharge tube is connected to two other different points of potential of the circuits for relay 11. In this case the two points are located along the inductance 16 so that when the resistance of tube 31 is broken down the effect is to place a radio frequency path having a substantial resistance component in shunt with a portion of inductance 6. In this case I prefer to dispense with the choke 44 and a single stopping condenser 42 is inserted between the inductance 16 and gas discharge tube 31, as the turns of inductance 16 across which the gas discharge tube is connected presents a short circuit path of low impedance for relatively low frequency currents originating in the gas discharge tube circuit. Choke 46 functions in the same manner as choke 46 of Figure 1.

20 I claim:

In a carrier wave receiving system, a source of signal energy of carrier frequency, an electron relay detector having a radio frequency input circuit adapted to receive energy from 25 said source, a radio frequency circuit associated with the output of said relay and adapted to feed energy into said input circuit whereby said relay is adapted to operate regeneratively, a gas discharge tube having 30 cold electrodes connected across points of different potential of said circuit, and means for exciting said gas discharge tube whereby it is caused to periodically vary its resistance.

35 In testimony whereof, I have hereunto set my hand.

HORACE E. OVERACKER.
